(57) **CLAIM**

The ornamental design for a flow controller for static mixer as shown and described.

DESCRIPTION

FIG. 1 is a perspective view showing an embodiment of the new design for a flow controller for static mixer;

FIG. 2 is a top view thereof, the bottom view being a mirror image;

FIG. 3 is a left side view thereof, the right side view being a mirror image; and,

FIG. 4 is a perspective view thereof in use, showing assembly of flow controller seated in static mixer.

The broken lines in the drawings are shown for illustrative purposes only and form no part of the claimed design. In addition, the surface shading illustrated in the drawings is provided merely to highlight contour of design; it is not intended to be illustrative of texture or gloss.
